UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

ENDLESS BELT AND METHOD OF MAKING THE SAME.

1,256,011.

Specification of Letters Patent. Patented Feb. 12, 1918.

Application filed March 24, 1913. Serial No. 756,320.

To all whom it may concern:

Be it known that I, JOHN R. GAMMETER, a citizen of the United States, residing at Akron, in the county of Summit and State of Ohio, have invented certain new and useful Improvements in Endless Belts and Methods of Making the Same, of which the following is a specification.

This invention has for its object the production of an endless driving belt which shall be of uniform tensile strength in all portions, and possessed of great flexibility and durability.

Of the accompanying drawings, Figure 1 represents a view of the spliced core strand.

Fig. 2 represents the cover strand being wound on.

Fig. 3 represents a portion of the completed belt body.

Fig. 4 represents a section of the belt provided with a rubber incasement.

As here shown, the cover strand is separate from the core strand. Although I could make one a continuation of the other, it is preferred to proceed as indicated in the drawings, according to which I first take a strand of rope or cord 10, and splice its ends as indicated at 11 to form an endless core. The principal use of the core is to furnish something on which to wind the cover strand, but when made of stranded or twisted fibrous threads, it also limits the extensibility of the belt. Next, the cover strand 12, which may also be made of twisted fibrous threads, has its end secured to the core with a binding of thread 13. This cover strand may conveniently be unwound from a storage reel 14, which is passed around and through the loop of the core strand, and the operation of winding may be performed by hand or in any other suitable way.

In winding the strand 12, it is wrapped around the core as an open or steep-pitched helix, the space between whose turns is so calculated as to leave room for the desired number of subsequent courses of the same strand in said space. The term "course" refers to one circuit of the helical winding. Thus, if the completed cover 15, of which a short length is shown in Fig. 3, is to constitute a five-“thread” helix, the initial spacing of the turns will be such as to admit four more turns constituting the succeeding courses, and the winding is continued until

all this space is filled. In other words, after 55 one belt-encircling course or wrapping of the cover-strand 12 has been laid on to the core or supporting strand 11, and brought around to the point where it was begun, the winding will be continued to lay a second 60 course adjacent to the first one, longitudinally of the belt, this second course being shown in Fig. 2 in process of being laid, and so on.

After the laying of helical courses has 65 been repeated until the entire core-strand is covered, the end of the cover-strand may be anchored in any suitable way, as by a binding of thread (not shown). The result is an endless round belt or cable whose body 70 winding has no splice in the proper sense, and hence is of uniform tensile strength in all parts, the belt being also capable of bending easily in any direction without causing undue tension on the outer side or compression on the inner side of the bend, which would tend to cause wear and breakage.

The belt body thus formed may be provided with a rubber coating 16 as shown in Fig. 4, applied in any well known or suitable way and forming the wearing surface of the belt. For example, the belt-body is dipped in rubber cement and wrapped with a covering of vulcanizable sheet rubber. The belt is then placed in an expanding 85 mold of appropriate construction and vulcanized under tension, whereby it is given a suitable external form, the stretch taken out, and the rubber caused to permanently coat and permeate the body. The vulcanized rubber binds together the fibrous courses and serves to hold all of the strands in their stretched, tense, or elongated condition. Such belts are particularly suited to driving light machinery, such as fans, for 90 example, but may be employed for many purposes.

The cover courses could, without departing from my invention, be wound somewhat more quickly with two or more strands at 100 the same time, as will be obvious without illustration, but I do not consider such a method as desirable as the one here represented.

I believe myself to be the first to form an 105 endless belt by winding a strand or cord of fibrous material helically in successive parallel courses, rubberizing said cord, and vul-

canizing the belt while under tension, and therefore do not confine the invention wholly to the exact shape or structure disclosed, or the exact details and order of the steps 5 herein set forth.

I claim:—

1. An endless, substantially non-stretchable belt comprising a tense strand of fibrous material wound in a continuous series of adjacent courses longitudinally of the belt, and vulcanized rubber serving to bind together said courses and hold them in their stretched condition.
- 10 2. An endless substantially non-stretchable belt comprising a tense endless spliced core-strand of fibrous material, a tense cover strand of fibrous material wound helically about said core-strand in a continuous series of belt-encircling courses, the turns of each 20 course lying between the turns of another course, and a vulcanized rubber coating forming the wearing surface of the belt, embedding and binding together the cover-strands and serving to hold the latter and 25 the core strand in their tense condition.
- 15 3. The method of forming a substantially non-stretchable endless belt which consists in winding a fibrous strand in a continuous series of adjacent courses longitudinally of 30 the belt, incorporating rubber with said

strand, and vulcanizing said rubber while the belt is held under tension.

4. The method of forming an endless belt which consists in winding a fibrous cord helically in a series of adjacent parallel courses, incorporating rubber therewith, stretching the belt and vulcanizing it as a whole while under tension.

5. The method of forming an endless belt which consists in winding a fibrous cord in successive parallel courses helically about a core so that the turns of each course lie between the turns of another course, incorporating rubber therewith, stretching the belt and vulcanizing it while under tension.

6. An endless, substantially non-stretchable belt comprising a tense strand of fibrous material wound in a series of adjacent parallel courses longitudinally of the belt, and vulcanized rubber within and at the surface 50 of the belt, serving to bind together and hold said courses in their stretched condition and to form a driving surface.

In testimony whereof I have hereunto set my hand in the presence of two subscribing 55 witnesses, this 8 day of March 1913.

JOHN R. GAMMETER.
